UNITED STATES PATENT OFFICE.

GALE G. REIS, OF DULUTH, MINNESOTA.

DEVICE FOR CLEANING GAS-VALVE SEATS.

Application filed September 17, 1921. Serial No. 501,503.

This invention relates to a new and improved device for cleaning gas valve seats and more particularly to a device of this character which may be operated without loss of the fluid controlled by the valves and without obstructing the valve passages.

In a battery of by-product coke ovens there are installed pipes which draw the gas from the ovens into the collecting mains. The mains run transversely of the battery of ovens and valves are located at the junction of the pipes and mains. The gas comes off the ovens at a high temperature and carries considerable free carbon in the form of soot or lamp black, and tar vapor.

This material is deposited upon the seat of the valve, and it is therefore necessary to periodically clean the valve seats. This must be done while the oven pipes and collecting mains are hot and full of gas.

Attempts have heretofore been made to clean these valve seats by introducing bars through small hand holes and knocking off the carbon.

It is an object of the present invention to provide a valve cleaning device which is adapted for cleaning valve seats in the situation described or under similar circumstances.

It is a further object to provide a cleaning device which may be operated without interrupting the flow of gas and without loss of gas.

An additional object is to provide a device which is operable from without the valve structure and which may be used while the pipes and valves are heated, and in use.

It is also an object to provide a new and improved method of utilizing such a device in cleaning valve seats.

Other and further objects will appear as the description proceeds.

Broadly, my invention comprises the provision of valve seat cleaning means operated through a closure; the latter being adapted to take the place of the usual valve cover. In a more specific form the valve cleaning means is supported by a collar; the collar being threaded into the closure member in such manner that the cleaning device may be raised or lowered relative to the closure and may be rotated in the sleeve.

I have illustrated a preferred embodiment of my invention in the accompanying drawings.

Figure 1 is a vertical cross section show-

ing portions of coke oven apparatus with my invention applied thereto.

Figure 2 is an enlarged vertical cross section of the cleaning apparatus associated with a valve, and

Figure 3 is a plan view of a temporary cover which may be used in installing my device.

Referring now to Figure 1; the coke oven 65 4 connects to the stand pipe 5 and from this pipe 5, the pipe 6 leads to the valve 7. The valve 7 connects to the gas main 8. In the structure shown, a pipe 9 leads through valve 10 to a second main 11. The valve 10 70 is provided with the closure 12 through which passes the valve stem 13, carrying the valve member 14. The chain 15 is connected to the valve stem 13 and leads over pulley 16 to the counter weight 17. The valve 7 75 is identical in construction with valve 10.

As shown in Figure 1, the parts of the valve 7 have been removed and replaced by my cleaning device, which latter is shown more in detail in Figure 2.

Referring now to Figure 2, the valve cover 12 has been replaced by a cover member 18 in which is threaded the sleeve 19. The sleeve 19 is provided at its upper end with the handle 20 by means of which it may be 80 rotated to move it upwardly or downwardly relative to the cover member 18.

Passing through the sleeve 19 is the shaft 21 which has fixed thereto the collar 22 bearing upon the upper end of the sleeve 19. 90 The shaft 21 is further provided with the handle 23 by means of which it may be rotated. To the lower end of the shaft 21 is keyed the tool holder 24 which carries the cutting or cleaning tools 25. The tool holder 24 is provided upon its upper face with the boss 26 which bears against the lower end of the sleeve 19, and upon its lower face with the boss 27. The boss 27 is equal to or greater than the cutting tools 25 in depth.

The temporary cover shown in Figure 3 is an imperforate disc 28 of a size sufficient to close the valve cover opening. It is provided with a lug or extension 29 to facilitate handling it.

In the use of my device the securing means for the valve cover 12 are loosened and the cover and valve are quickly removed. As they are removed the plate 28 is slipped in place. A small amount of gas will escape but the change can be made so rapidly that the amount escaping is negligible. The clean-

ing tool is next placed upon the plate 28, the boss 27 resting upon the plate. The plate 28 is then quickly withdrawn and the cutting tool slips within the valve chamber and the 5 cover member 18 completely closes the valve opening.

The sleeve 19 is next rotated by means of the handle 20 until the cutting tools 25 are brought to bear against the valve seat 30 as 10 indicated in dotted lines in Figure 2. The tools are then rotated by means of the handle 23 to clean the valve seat. The tools may be fed downwardly during the cleaning by 15 screwing down the sleeve 19. In removing the tool the process carried out in putting it in place is gone through in reverse order.

The use of the temporary cover member 28, while not absolutely necessary is highly desirable in order to minimize the escape of gas 20 while removing the valve and getting the cleaning device in place.

In the use of my device, the valve seat may be cleaned much more uniformly than is possible by the insertion of bars as is now 25 customary. Further, by the use of cutting tools the valve may be reseated. The tools and tool holder do not completely close the valve opening and gas may continue to pass while the tool is being used.

30 It is my intention to cover all modifications of my device coming within the spirit and scope of the following claims.

I claim:

35 1. In a valve seat cleaning device, a cover member adapted to replace the valve cover, a

sleeve threaded in the cover, and a cleaning member supported in the sleeve, means adapted to rotate the sleeve to move it in and out of the cover and means adapted to rotate the cleaning member relative to the 40 sleeve.

2. The method of cleaning valve seats comprising removing the valve cover and valve member, temporarily covering the opening, positioning a cleaning apparatus 45 on the said covering means, withdrawing the covering means and quickly inserting the apparatus closing the valve cover opening by means of a portion of said apparatus and operating the cleaning apparatus from the 50 exterior of the valve.

3. A valve seat cleaning device, comprising a cover member and a cleaning member carried by the cover member and adapted to engage the valve seat, said cleaning member being less in area than the valve opening 55 whereby gas may pass through said opening during the cleaning operation.

4. In a valve seat cleaning device, a cover member adapted to replace the valve cover, a sleeve threaded in the cover member, a shaft supported in said sleeve and rotatable therein, a tool holder carried on the lower end of said shaft, valve seat engaging tools extending downwardly from the holder, and a central boss on the holder extending downwardly not less than the depth of the tools. 60 65

Signed at Duluth, Minn., this 9th day of Sept., 1921.

GALE G. REIS.
